UNITED STATES PATENT OFFICE.

DAVID F. CURTIN, OF CHICAGO, ILLINOIS.

POCKET PENCIL HOLDER.

Application filed August 30, 1920. Serial No. 406,962.

To all whom it may concern:

Be it known that I, DAVID F. CURTIN, a citizen of the United States, and a resident of the city of Chicago, in the county of Cook and State of Illinois, have invented certain new and useful Improvements in a Pocket Pencil Holder; and I do hereby declare that the following is a full, clear, and exact description of the same, reference being had to the accompanying drawings and to the numerals of reference marked thereon, which form a part of this specification.

This invention relates more particularly to an improved pocket extender adapted to be removably inserted in a pocket of a garment to hold pencils and other articles in place without preventing insertion or removal of the pencils or articles.

It is an object of this invention to provide a spring controlled device adapted, when inserted in a pocket, to stretch the pocket to cause the pocket walls to engage pencils and other articles to hold the same in place against accidental removal.

Another object of the invention is to provide a pocket extender embracing spring controlled telescoping members adapted when disposed within a pocket to hold pens and pencils in place without preventing insertion or removal of said pens and pencils.

It is also an object of the invention to construct a pocket extender wherein toothed spring controlled co-acting members are adapted to be disposed between the pocket walls to hold pencils in place and preventing them from falling out of the pocket when it is inverted.

It is an important object of this invention to provide a pocket pencil holder of simple and inexpensive construction adapted to be inserted between the walls of a pocket to tension said walls thereby causing the same to act as retainers for holding pencils and other articles in the pocket.

Other and further important objects of this invention will be apparent from the disclosures in the drawings and specification.

The invention (in a preferred form) is illustrated in the drawings and hereinafter more fully described.

On the drawings:

Figure 1 is a fragmentary elevation of a garment having a pocket provided with a holder device embodying the principles of this invention.

Figure 2 is an enlarged sectional view taken on line 2-2 of Figure 1.

Figure 3 is a front elevation of the device showing hidden parts and the operation in dotted lines.

Figure 4 is a section taken on line 4-4 of Figure 3.

Figure 5 is a section taken on line 5-5 of Figure 3.

Figure 6 is a sectional interior elevation taken on line 6-6 of Figure 5.

Figure 7 is a similar view of a modified form of the device.

Figure 8 is a similar view of another modified form of the device.

As shown on the drawings:

The reference numeral 1 indicates a garment or more specifically a vest provided with a breast pocket 2 of usual construction and having disposed therein a note book 3 and a pencil 4 placed on opposite sides of an improved holder.

Figures 3 to 6 inclusive illustrate a preferred form of improved pencil holder which comprises a body or flat outer sleeve 5 made of thin metal, fiber or tough waterproof paper. The outer sleeve 5 is made of a sheet of paper or other material folded over at 6 and at 7 to permit the end margins to overlap and be secured together at 8. One end of the flat sleeve 5 has the edges cut or notched to afford teeth 9. Secured by means of an eyelet 10 in one corner of the sleeve 5 between the side walls of said sleeve is one end of a wire spring 11 the other end of which projects into a secondary or inner body or sleeve 12 and is secured thereto by means of an eyelet 13.

The inner sleeve 12 is made by folding a piece of waterproof paper or other material over at 14 to afford two sides, the outer edges of which are cut or notched to provide teeth 15. The lower margins of the sides of the inner sleeve are not secured together. The inner sleeve 12 is connected with the outer sleeve 5 by means of the spring 11. When the holder is to be used in a pocket the inner sleeve 12 is telescoped into the outer sleeve

5 thereby compressing the spring 11. By 105 pressing the walls of the outer sleeve together the inner sleeve is held in place against the action of the spring 11 until the holder is inserted into the pocket 2. Upon releasing the sides of the outer sleeve 110 the spring 11 acts automatically to slide the two sleeves outwardly with respect to one

another thereby forcing the toothed edges of the sleeves against the side seams of the pocket. The pocket walls are thus tensioned or drawn taut, thereby causing the pencil 4 and the book 3 to be held in place within the pocket and against the sides of the holder. The holder thus serves as a medium for holding articles such as pencils, fountain pens and the like in their proper place within a pocket.

In the modified form of the device illustrated in Figure 7, a flat inner sleeve 16 is telescoped into a flat outer sleeve 17 and is connected therewith by two wire springs 18 and 19 which are bent or arched in opposite directions. The opposite ends of the springs 18 and 19 are respectively secured by means of eyelets within the respective telescoping sleeves 16 and 17. The outer or end edges of the sleeves 16 and 17 are cut or notched to provide teeth 20. The inner corners of the inner flat sleeve 16 are cut away at 21 to permit the inner sleeve to be easily inserted into the flat outer sleeve. In this construction the operation is the same as that hereinbefore described, the double spring arrangement exerting a greater tensional stress on the walls of a pocket than the single spring device illustrated in Figure 6.

Figure 8 discloses another modified form of pencil holder comprising a sheet of heavy waterproof paper or other material which is folded in half at 22 to form a two wall body 23. Secured between the walls of the body 23 by eyelets 24 and 25 is a flat metal brace arm or bar 26 which is disposed at an angle to the center line of the body 23 as shown in Figure 8. The upper portion of the arm 26 projects through the open side edge of the body and is cut to afford projecting teeth 27. Pivotedly mounted on the lower eyelet 25 between the walls of the body 23, is the lower end of a second plate or bar 28 the upper side edge of which is cut off and notched to afford teeth 29. Attached to the eyelet 24 between the stationary arm 26 and one of the body walls is one end of a wire spring 30 the other end of which is connected to the upper or free end of the pivoted arm 28 by an eyelet 31. The spring 30 acts to normally hold the pivoted arm 28 projected out through one side edge of the body into the dotted line portion of Figure 8. To place the pencil holder in a pocket the pivoted arm is forced into the body 23 against the action of the spring 30 which is compressed. When the holder is in place within a pocket the spring 30 acts to force the free end of the arm 28 outwardly thereby causing the teeth 27 and 29 of the arms 26 and 28 respectively to engage against the side seams of the pocket to tension the pocket walls. Pencils or other arti-

cles in the pocket are thus held in place against the walls of the holder.

I am aware that numerous details of construction may be varied through a wide range without departing from the principles of this invention, and I therefore do not purpose limiting the patent granted otherwise than necessitated by the prior art.

I claim as my invention:

1. A pocket pencil holder, comprising a pair of members of similar construction telescoping one with the other, and resilient means connecting the same and acting to hold said members extended with respect to one another.

2. A pocket pencil holder comprising two slidably interfitting members, teeth formed on the outer end edges thereof, and resilient means connecting the outer ends of said members.

3. A pocket article holder embracing a flat sleeve, a second sleeve telescoped into the first sleeve, and a bow spring connected to said first sleeve and to said second sleeve acting to hold the second sleeve extended from said first sleeve.

4. The combination with a pocket, of a pair of similarly constructed spring connected members disposed therein and telescoping one within the other to tension the walls of the pocket to hold pencils and other articles in place within the pocket.

5. The combination with a pocket, of a pair of toothed telescoping members disposed longitudinally within the pocket, and resilient means connecting the outer ends of said members and enclosed by said members adapted to hold the members extended to tension the walls of the pocket.

6. The combination with a pocket, of a pencil holder therein comprising a flat outer sleeve, teeth formed on one edge thereof, a flat inner sleeve slidably engaged in said flat outer sleeve, teeth formed on one edge of said inner sleeve, and resilient means enclosed by said sleeves to hold the same projected with respect to one another to tension the walls of the pocket.

7. The combination with a pocket, of an article holder therein comprising a flat body, means adjustably engaged therein, teeth formed on said means to afford a gripping edge, and a spring having one end secured to said body and the other end connected to said means to hold said means projected to tension the pocket walls.

In testimony whereof I have hereunto subscribed my name in the presence of two subscribing witnesses.

DAVID F. CURTIN.
